US00D825593S

(12) **United States Design Patent** (10) Patent No.: **US D825,593 S**
Siccardi et al. (45) Date of Patent: **** Aug. 14, 2018**

(54) **DISPLAY SCREEN OR PORTION THEREOF
WITH GRAPHICAL USER INTERFACE**

(71) Applicant: **Medacta International SA**, Castel San Pietro (CH)

(72) Inventors: **Francesco Siccardi**, Castel San Pietro (CH); **Gianluca Olgiati**, Castel San Pietro (CH); **Marco Cavagna**, Castel San Pietro (CH)

(73) Assignee: **MEDACTA INTERNATIONAL SA**,
Castel San Pietro (CH)

(**) Term: **15 Years**

(21) Appl. No.: 29/591,398

(22) Filed: **Jan. 19, 2017**

(30) **Foreign Application Priority Data**
